(57) CLAIM

The ornamental design for a hook, as shown and described.

DESCRIPTION

FIG. 1 is a perspective view of hook, with the present invention;

FIG. 2 is a front elevational view of the hook shown in FIG. 1;

FIG. 3 is a top plan view of the hook shown in FIG. 1;

FIG. 4 is a bottom plan view of the hook shown in FIG. 1;

FIG. 5 is a right side elevational view of the hook shown in FIG. 1; and,

FIG. 6 is a perspective view of the hook shown in FIG. 1, but shown in a condition of use.

The broken line depiction of a magnet shown in FIG. 2, 3, 4, and 5 views as well as the broken line depiction of environmental structure in the FIG. 6 view are both for illustrative purposes only and form no part of the claimed design. The back of the hook, which has not been depicted, also forms no part of the claimed design.
